ABRAHAM M. SOUTHARD AND GEORGE W. SMITH, OF DENVER, COLORADO;
SAID SMITH ASSIGNOR TO SAID SOUTHARD AND JOHN H. BLOOD, OF
SAME PLACE.

SCREW-BEADING MACHINE.

SPECIFICATION forming part of Letters Patent No. 450,262, dated April 14, 1891.

Application filed September 16, 1890. Serial No. 365,190. (No model.)

To all whom it may concern:

Be it known that we, ABRAHAM M. SOUTHARD and GEORGE W. SMITH, both citizens of the United States of America, residing at Denver, in the county of Arapahoe and State of Colorado, have invented certain new and useful Improvements in Screw - Beading Machines; and we do declare the following to be a full, clear, and exact description of the invention, such as will enable others skilled in the art to which it appertains to make and use the same, reference being had to the accompanying drawings, and to the figures of reference marked thereon, which form a part of this specification.

Our invention relates to an improved form and construction of devices whereby the ordinary beader or beading-machine used by tinsmiths is transformed into a machine capable of forming screw-threads on the joining extremities of all kinds of light metal pipes or tubing, such as stove-pipes, heating-pipes leading from furnaces, speaking-tubes, and all kinds of sheet-metal conduits for hot or cold air, smoke, sound, &c. The inconvenience, trouble, and vexatious delay nearly always experienced in joining the extremities of pipes of this class in the ordinary way are too well known to need further comment. Hence the object of our improvement is to form a machine of the class stated which shall be simple in construction, economical in cost, easily operated, and durable.

To these ends our invention consists of the features hereinafter described and claimed.

In the accompanying drawings is illustrated an embodiment of the invention, in which drawings—

Figure 1 is an elevation of an ordinary beading-machine provided with our improved attachments, the standard or support for the machine being shown partially broken away. Fig. 2 is a vertical section taken through the line $x-x$, Fig. 1, looking toward the right. Fig. 3 is a longitudinal section, partially broken away, taken through one of the rollers provided with a removable threaded sleeve. Fig. 4 is an elevation in detail of the gage of the machine, showing the half-nut or threaded lug, which, when the parts are assembled, en-

gages the threaded shaft. Fig. 5 shows an elevation of the threaded extremity of a section of pipe. This view is designed to illustrate the work which the machine will accomplish:

In the views, wherein similar reference-characters indicate corresponding parts of the mechanism, let the numeral 1 designate the frame-work of the ordinary beading-machine supported upon a standard 2, resting on a base. (Not shown.) Within the frame is suitably journaled and supported the shafts 3 and 4, provided with a cog-wheel 5, secured to each shaft. These cog-wheels mesh with each other, so that when one shaft is rotated motion is also communicated to the other.

The numeral 6 designates a suitable crank secured to shaft 3, a crank being the means usually employed for applying power to this class of machines.

Secured to the outer extremities of the shafts are the bead-rolls 7 and 8. Roll 7 is provided with a circumferential groove and roll 8 with a corresponding tongue, the tongue and the groove coacting in forming the bead upon a section of sheet-metal pipe or tubing so placed with reference to the rolls that one roll engages the interior and the other the exterior of the pipe or tube.

9 is an adjustable gage, which engages the end of the section of pipe or tube acted upon, by means of which gage the distance of the bead from the end of the tube acted upon is regulated, the gage being held stationary during the operation of beading. Such is the ordinary beading-machine.

Our improvement consists in forming a screw-thread 10 upon one shaft, providing the gage with a correspondingly-threaded half-nut, and permitting the gage to move freely upon the guides.

As shown in the drawings, shaft 3 is provided with the screw-thread 10. This thread may be formed upon the solid shaft. It is deemed preferable, however, to provide the shaft with a removable threaded sleeve 11, as shown in Fig. 3, the shaft being provided with a lug 12, adapted to enter a corresponding recess in the sleeve at one extremity, while at the opposite extremity the sleeve is

provided with a lug 13, entering a corresponding recess formed in roll 7. Thus the sleeve is held securely in place upon the shaft, but may be quickly and easily removed and a 5 differently-threaded sleeve substituted therefor, or when for any other reason the removal of the sleeve is considered necessary or desirable. The gage is provided on the side adjacent to shaft 3 with a half-nut 14, secured 10 in place by a countersunk screw 15. This nut is threaded to correspond with the threads 11 upon the shaft, the nut engaging the threaded portion of the shaft during the operation of the machine.

15 The screw 16 of the ordinary beading machine enters the guide 17 and holds the gage stationary during the operation of the machine in forming a bead, there being no feed to the gage, as before stated.

20 In the use of our improved machine the set-screw 16 is either removed or loosened, so that it will not engage the guide or guides, which must slide freely through the frame.

The operation of our improved machine will 25 be readily understood. By turning a top screw 18, with which the beading machine is provided, the rolls are so adjusted that one extremity of a section of pipe may be placed in position, one roll being on the interior and 30 the other on the exterior surface. The machine is now properly adjusted by reversing the action of screw 18 until the rolls engage the pipe sufficiently tight, the gage having been first adjusted so as to engage the end 35 of the pipe. By turning the crank a screw bead or thread is now formed upon the pipe, which is forced outward by the gage, the bead or thread being started at a distance from the end of the pipe equal to the desired length of 40 the threaded portion.

The advantages of having the joining extremities of stove-pipes and similar pipes or tubes threaded instead of employing the old

method of sliding the end of one section into the end of the other section in forming the joints are obviously numerous. Among these advantages may be mentioned the ease of forming the screw-joints and their greater security, there being at the same time a considerable saving of material since no supporting-wires are needed with the screw-joint pipe, and there is no necessity for overlapping the ends of the sections so far in forming the screw-joint as the ordinary joint, thus making a considerable saving in this item alone. 55

Having thus described our invention, what we claim is—

1. The combination, in a machine for forming screw-threads upon the extremities of sheet-metal pipes or tubes, of a frame, a pair 60 of shafts journaled therein, a pair of coacting bead-rolls mounted upon the shafts, one of said shafts being provided with a threaded portion, a gage slidably supported between the shafts and provided with a feeding attachment consisting of a half-nut or threaded lug adapted to engage one side of the threaded shaft, substantially as and for the purpose set forth.

2. The combination, with a frame, of a pair 70 of shafts journaled therein, a pair of beading-rolls mounted upon the shafts, one of said shafts being provided with a removable screw-threaded sleeve, a gage slidably supported between the shafts and provided with a feeding attachment consisting of a half-nut or threaded lug adapted to engage the threaded sleeve on the shaft, and suitable means of rotating the shafts, substantially as described. 75

In testimony whereof we affix our signatures 80 in presence of two witnesses.

ABRAHAM M. SOUTHARD.
GEORGE W. SMITH.
